United States Patent Office

Des. 181,379
Patented Nov. 5, 1957

181,379

LAUNDRY MACHINE CABINET OR SIMILAR ARTICLE

Carl W. Sundberg, Birmingham, Mich., assignor, by mesne
assignments, to Whirlpool-Seeger Corporation, St.
Joseph, Mich., a corporation of Delaware

Application August 11, 1955, Serial No. 37,417

Term of patent 14 years

(Cl. D49—1)

FIG. 2

FIG. 1

Figure 1 is a front perspective view of a laundry machine cabinet or similar article showing my new design; and

Figure 2 is a fragmentary side elevation thereof with portions omitted for convenience of illustration.

The essential features of the design reside in the portions shown in full lines.

I claim:

The ornamental design for a laundry machine cabinet or similar article, as shown and described.
